UNITED STATES PATENT OFFICE.

JOHN EDWARD HIGH, OF DICKINSON, NORTH DAKOTA.

PLATE-LIFTER.

1,035,088.

Specification of Letters Patent.

Patented Aug. 6, 1912.

Application filed June 20, 1911. Serial No. 634,218.

To all whom it may concern:

Be it known that I, JOHN EDWARD HIGH, a citizen of the United States, residing at Dickinson, in the county of Stark and State 5 of North Dakota, have invented certain new and useful Improvements in Plate-Lifters, of which the following is a specification.

My invention relates to improvements in plate lifters and has for its object the pro- 10 vision of an improved readily adjustable device of this character adapted for use in handling various sizes of dishes or saucers which will readily grasp and firmly engage the article to be lifted irrespective of the 15 size of said article and which will be of extremely simple construction.

To attain the desired object my invention comprises a plate lifter substantially as il- 20 lustrated and as hereinafter described, but it will be understood that any changes in 25 the details of construction within the scope of the claim may be made without departing from the spirit of the invention.

Figure 1 represents a side elevation of 25 the plate lifter, Fig. 2 represents a top plan view thereof. Fig. 3 represents a similar view showing the lifter engaging a sauce dish, and Fig. 4 represents a longitudinal 30 sectional view of the lifter. Fig. 5 represents a perspective view of the device em- 35 ployed in lifting a cup, and Fig. 6 represents a plan view of one of the end or cap plates for the handle.

In the drawings, the numeral 1 denotes 35 the flexible spring steel band having its ends united as by the rivets 2 to form an endless band therefrom. Mounted on the intermediate portion of the band is the cylindrical member 3 providing a handle, said member 40 having secured at each end the cap plate 4 having slots 5 therein at diametrically op- 45 posite points through which the intermediate portions of the band pass as most clearly shown in Fig. 4.

From the foregoing description taken in connection with the drawings it will be seen

that I provide an endless steel band having a cylindrical handle forming member slidably engaged on the intermediate portion of the band to hold the intermediate 50 portions thereof together and provide a loop 6 on each end of the handle.

To lift a pan, dish or other article I en- 55 gage one of the loops around said article and then grasp the cylinder or handle with one hand and the free loop with the other, and slide the cylinder toward the article to be lifted, decreasing the size of the loop surrounding the article to cause the loop of the band to tightly engage the periphery 60 of the article.

It will thus be seen that I have provided a simple but efficient plate lifter which has an engaging loop at each end thereof adapt- 65 ed to be interchangeably employed for en- gaging an article, and that on account of the endless construction of the band the loop can be readily made large enough to engage a dish of considerable size or small enough to engage a sauce dish or a doll's 70 cup.

I claim:

A plate lifter comprising an endless 75 spring steel band, a cylindrical member mounted on the band to hold opposite por- 80 tions thereof in juxtaposition and a cap plate for each end of said cylindrical mem- 85 ber, each of said cap plates having a pair of diametrically opposite slots formed there- in through which the opposite sides of the band extend, the band thus providing an engaging loop at each end of the article adapted to be interchangeably used, the movement of the cylindrical member on the band decreasing the size of one of the loops to clamp it on an article.

In testimony whereof I affix my signature, in the presence of two witnesses.

JOHN EDWARD HIGH.

Witnesses:

L. R. HART,
THOMAS BURKE.
